J. J. Vedder, of Troy, N.Y.

Assignor to

Graham F. Phillips, same place,
Letters Patent No. 32. Dated April 2, 1861.

Whole No. 1397.

The schedule referred to in these Letters Patent and making part of the same.

To all whom it may concern:

Be it known that J. J. Vedder, of the City of Troy, in the County of Rensselaer, and State of New York, have invented or produced a certain new and original ornamental design for Elevated oven, Cookers, Stoves, and I do hereby declare that the following is a full and exact description thereof, reference being had to the annexed photographic drawing which makes a part of this Specification.

Des. 1397

My ornamental design for Elevated. Oven Cooking Stoves consists of the ornaments, a, a, the horizontal, vertical, and overarching panel mouldings, b, b, scale work, c, and ornaments, d, on the front plate, I, of the oven; the ornament, f, horizontal, vertical, and overarching moulding, g, and border moulding, h, of the door, I, at the end of the oven; and the ornament, j, and border moulding, k, on the front door I, I, of the fire box. the whole formed and arranged as represented by the annexed photographic drawing.

What I claim as my invention or production, and desire to secure by Letters Patent, is the ornamental design for an Elevated. oven Cooking Stove herein described and represented in the annexed photographic drawing.
